George W. Romaine,
BY A. M. Pierce,

ATTORNEY.

UNITED STATES PATENT OFFICE.

GEORGE W. ROMAINE, OF NEW YORK, N. Y.

PLACKET-CLOSER.

SPECIFICATION forming part of Letters Patent No. 693,623, dated February 18, 1902.

Application filed September 9, 1901. Serial No. 74,777. (No model.)

To all whom it may concern:

Be it known that I, GEORGE W. ROMAINE, a citizen of the United States, residing in the city, county, and State of New York, have 5 invented a new and useful Improvement in Placket-Closers, of which the following is a specification.

My invention relates especially to devices employed for closing the openings in garments at the meeting parts thereof, and has for its object the provision of a cheap, simple, and effective device for closing the plackets in dress-skirts and the like.

To attain the desired end, my invention 15 consists, essentially, in a plate of metal having a longitudinal slot extending for a part of the length of the plate, the body of the plate having a bent or curved portion near the center of the slot and at right angles thereto, 20 said plate being secured to one flap of the placket to be closed, in combination with a button or stud secured to the opposite flap of the placket and arranged to engage the slot in the plate, all of which will be hereinafter 25 first fully described and then pointed out in the claims.

In the accompanying drawings, forming a part hereof, Figure 1 is a plan view of the slotted plate of my invention, and Fig. 2 is a 30 side elevation thereof. Fig. 3 is a side elevation, and Fig. 4 is a plan view, of the button or stud. Fig. 5 is a view of a fragment of a placket, the parts of my closer being shown in dotted lines. Fig. 6 is a vertical sectional view at line $x-x$ of Fig. 5.

Similar numerals of reference wherever they occur indicate corresponding parts in all the figures.

1 is the body of the plate, made of any approved material and having a longitudinal slot 2 therein, open at the upper part and constricted near its center, the lower end of the slot terminating in an enlargement 3.

4 represents perforations for the reception 45 of thread for securing the plate to the fabric of a garment.

6 is the bent or curved portion of the plate.

7 represents the belt of a skirt, and 8 and 9 the flaps of the placket. The plate 1 is 50 secured to one of the flaps in a vertical position and a button or stud 5 to the opposite flap in

the proper relative position to the plate, using as many plates and buttons or studs as the adequate closing of the placket may require.

In closing the placket the wide portion of 55 the slot in the plate permits the easy introduction of the shank of the button or stud, the shank being preferably thicker than the width of the constricted part of the slot, and in its passage downward the spring of the 60 metal of the plate permits the two prongs to spread, the shank of the button or stud finally coming to rest at the enlarged extremity of the slot below the curved raise of the metal of the plate. When the parts are all in the 65 positions indicated in Figs. 5 and 6 and the skirt is raised, the curve of the plate and the spring of the metal effectually prevent the escape of the shank of the button or stud from the plate, and if the pull is to either side the 70 enlargement at the bottom of the slot assists in keeping the parts in position, thus positively preventing the opening of the placket.

Having now fully described my invention, what I claim as new therein, and desire to secure by Letters Patent, is—

1. A placket-closer in which is comprised a plate of metal having a transverse curved or bent portion and provided with a longitudinal slot extending through the curved or bent 80 portion of the plate and open at one end and constricted near its center, in combination with a button or stud adapted and arranged to engage in said slot, substantially as shown and described.

2. In a placket-closer, a plate of metal having a transverse curved or bent portion and a longitudinal slot extending through the bent or curved portion of the plate and open at one end, constricted near its center, and enlarged at the extremity opposite to the opening, in combination with a button or stud adapted and arranged to engage in the slot in the plate, substantially as shown and described.

3. In a placket-closer the combination with a stud, of a catch device with which the stud engages having a longitudinal slot, the opposite sides of the slot being throughout a portion of their course curved or bent in a substantially similar manner, whereby they remain substantially parallel with each other,

while the course of the slot is diverted, substantially as set forth.

4. In a placket-closer the combination with a stud, of a catch device with which the stud 5 engages having a longitudinal slot formed therein, the portions of the plate in which the opposite ends of the slot are formed being in substantially the same plane and the intermediate slotted portion of the plate being

bent out of such plane, substantially as set forth.

Signed by me at New York this 6th day of September, 1901.

GEORGE W. ROMAINE.
